United States Patent Office

Des. 219,860
Patented Feb. 2, 1971

219,860

PORTABLE ILLUMINATED SIGN

Stephen L. Burts and Dennis G. Jones, both of 4306
Hamilton Road, Columbus, Ga. 31902

Filed Oct. 30, 1969, Ser. No. 19,847

Term of patent 14 years

Int. Cl. D20—03

U.S. Cl. D96—12

FIG. 1

FIG. 2

FIG. 3

FIG. 4

FIG. 5

FIG. 1 is a side elevational view of a portable illuminated sign showing our new design, the opposite side being a mirror image of the side shown.

FIG. 2 is a top plan view thereof.

FIG. 3 is a front elevation thereof.

FIG. 4 is a rear elevation thereof.

FIG. 5 is an enlarged horizontal section, partially broken away, on the line 5—5 of FIG. 1.

We claim:

The ornamental design for a portable illuminated sign, as shown and described.
